(57) **CLAIM**

We claim the ornamental design for a bumper for a robotic vacuum cleaner, as shown and described.

DESCRIPTION

FIG. 1 is a perspective view of a bumper for a robotic vacuum cleaner, showing the new design;

FIG. 2 is a top view thereof;

FIG. 3 is a right side view thereof;

FIG. 4 is a left side view thereof;

FIG. 5 is a front view thereof; and,

FIG. 6 is a rear view thereof.

Broken lines are used in the drawings to illustrate features that form no part of the claimed design.

1 Claim, 4 Drawing Sheets
